UNITED STATES PATENT OFFICE.

WILLIAM HENRY INNES BRADLEY, OF BIRMINGHAM, ENGLAND, ASSIGNOR TO THE CALSO HOOD COMPANY LIMITED, OF COVENTRY, ENGLAND, A COMPANY OF GREAT BRITAIN.

FOLDING HOOD FOR MOTOR VEHICLES.

Application filed June 12, 1924. Serial No. 719,683.

To all whom it may concern:

Be it known that I, WILLIAM HENRY INNES BRADLEY, a subject of the King of Great Britain, residing at 28 Castleford 5 Road, Sparkhill, Birmingham, in the county of Warwick, England, have invented certain new and useful Improvements in Folding Hoods for Motor Vehicles, of which the following is a specification.

10 This invention relates to folding hoods for motor vehicles and more particularly where the hood is supported at each side by a single vertical standard pivoted in the body.

15 As at present constructed the upper ends of these standards carry a hood stick or bow rigidly secured thereto or formed in one piece therewith. In folding the hood it is necessary for this bow to clear the back 20 of the body or at least the back of the rear seats, consequently the position of the pivotal point of the standard in the body with respect to the back of the latter is limited and determined by the height of the 25 hood when extended.

30 The object of the present invention is to provide for cases where it is desired to pivot the standards so far forward as to allow for the provision of a window of substantial dimensions rearward of said standard without making the hood of undue height when extended and yet so that the bow will clear the rear seats when collapsed.

35 According to the present invention the bow, hereinafter referred to as the main bow, which formerly was carried by or formed in one with the standards, is carried in such a manner that it has a variable position with respect to said standards as the 40 hood is raised and lowered, so that when the hood is folded down the said bow will always clear the back of the body or rear seats irrespective of the position of the pivotal points of the standards in relation 45 to the latter.

50 In order that the invention may be clearly understood and readily carried into practical effect reference is made in further describing the same to the accompanying drawing, wherein,

Figure 1 is a view in side elevation of a hood fully extended and embodying the present invention.

55 Figure 2 is a side view of the hood mechanism in a partly collapsed state.

In both figures like parts are designated by similar reference characters.

In the particular application of the invention shown in the drawings it will be observed, more clearly perhaps from Figure 60 2, that the main bow 2 has no direct connection with the main standards 3 but is carried independently by the linkage of the hood in such a manner that it has a variable position with respect to such standard as the hood 65 is raised and lowered, that is to say, that as the hood is raised the main bow 2 moves inwardly toward the standard 3 until the hood is fully extended when it occupies a position close to and preferably in alignment with 70 the said standard as shewn in Figure 1. As the hood is lowered however the main bow is caused to move outwardly away from the main standard and when the hood is 75 fully collapsed the said bow overhangs the back of the body or rear seats 4 as will be gathered from Figure 2.

In the construction shewn this relative movement of the main bow is effected by supporting it at each end by a pair of links 80 one, 5, of which is pivoted at 6 in a rear extension 7 of the cantrail 8 whilst the other link 9 is pivoted at 10 in an intermediate bow member 11 which is itself pivoted at 12 in the cantrail 8.

85 Preferably the two links 5 and 9 are independently pivoted on different centres 13, 14 respectively to the end of the bow 2 so that any tendency for the latter to swivel out of position is eliminated.

90 In the type of hood shewn the rear bow 15 is pivoted to the rear end of the intermediate bow member 11 whilst the front bow 16 is pivoted to the forward end of the cantrail 8 and supported from the intermediate bow by the link 17. A lever 18 pivoted in the upper end of the standard 3 has its forward end pivoted in the intermediate bow member and its rear end connected by a link 19 with the rear bow member. The several bow members which carry the flexible cover 20 are therefore all pivotally interconnected with each other.

95 It will of course be obvious that the invention can be applied to hoods having other kinds of linkage than that shewn. The arrangement in every case is such that the distance between the bow 2 and the pivotal point 21 of the standard 3 in the body is increased as the hood is folded down so 100 105 110

as to clear the back of the body and correspondingly decreased when the hood is extended.

I claim:—

- 5 1. A folding hood for motor vehicles comprising, a standard pivotally mounted at each side of the vehicle, a cantrail pivoted adjacent the upper end thereof, a front bow member pivoted to the forward end of said cantrail an intermediate bow member pivoted in said cantrail, a rear bow member pivoted to the rear end of said intermediate bow member, a main bow member pivotally supported from said cantrail 10 and intermediate bow member independently of said standard and a flexible cover carried by said bow members.
2. A folding hood for motor vehicles comprising, a standard pivotally mounted at each side of the vehicle, a cantrail pivoted adjacent the upper end thereof, a front bow member pivoted to the forward end of said cantrail an intermediate bow member pivoted in said cantrail, a rear bow member pivoted to the rear end of said intermediate bow member, a main bow mem- 20 25

ber, links pivotally connecting the same respectively with the rear end of said cantrail and with the intermediate bow member, and a flexible cover carried by said bow mem- 30 bers.

3. A folding hood for motor vehicles comprising, a standard pivotally mounted at each side of the vehicle, a cantrail pivoted adjacent the upper end thereof, a front bow member pivoted to the forward end of said cantrail an intermediate bow member pivoted in said cantrail, a link connecting the front and intermediate bow members, a lever pivoted in the upper end of said standard and having its forward end pivoted to the intermediate bow member, a rear bow member pivoted to the rear end of said intermediate bow member, a link connecting the other end of said lever with the rear bow member, a main bow member links supporting the same from the rear end of said cantrail and from the intermediate bow member and a flexible cover carried by said bow members. 35 40 45

WILLIAM HENRY INNES BRADLEY.
